UNITED STATES PATENT OFFICE.

GEORGE B. MONK, OF SAN FRANCISCO, CALIFORNIA.

DESIGN FOR AN EMBLEM, BADGE, BUTTON, PIN, OR ARTICLE OF A SIMILAR NATURE.

60,943.

Specification for Design.

Patented May 9, 1922.

Application filed December 7, 1921. Serial No. 520,751. Term of patent 3½ years.

To all whom it may concern:

Be it known that I, GEORGE B. MONK, a citizen of the United States, residing at the city and county of San Francisco, State of California, have invented a new, original, and ornamental Design for an Emblem, Badge, Button, Pin, or Article of a Similar Nature, of which the following is a specification, reference being had to the accompanying drawing, forming part thereof.

The figure is a plan view of an emblem or insignia, showing my new design.

I claim:

The ornamental design for an emblem, badge, button, pin or article of a similar nature, as shown.

GEORGE B. MONK.
